UNITED STATES PATENT OFFICE

164,337

ASH TRAY

Wagn Trautner, Cincinnati, Ohio

Application June 27, 1950, Serial No. 10,771

Term of patent 14 years

(Cl. D85—2)

To all whom it may concern:

Be it known that I, Wagn Trautner, a citizen of the United States, residing at Cincinnati, in the county of Hamilton and State of Ohio, have invented a new, original, and ornamental Design for an Ash Tray, of which the following is a specification, reference being had to the accompanying drawings, forming a part thereof.

I claim:

The ornamental design for an ash tray, substantially as shown.

WAGN TRAUTNER.
